[57] ABSTRACT

The temperature of water within the tubular reservoir of a baseboard heater or the like is sensed through its end cap. The cap has an outstanding annular flange, and on its end has a planar indentation to seat the temperature-sensing face of a thermoswitch. A spring clip with outstanding spring-like leg portions, slotted to fit onto the cap flange, presses the temperature-sensing face of the thermoswitch into close contact with the surface of the planar indentation. In addition to low cost fabrication and ease of installing and changing, there is an improved response of the thermoswitch to the temperature of the liquid.

FIG. 4

FIG. 3

FIG. 2

FIG. 1

MOUNTING INSTALLATION FOR TEMPERATURE SENSING SWITCH

BACKGROUND OF THE INVENTION

Temperature-responsive electrical switches are conventionally used as limit switches to control heating of fluids as in circulation hot water systems. Where the liquid is contained in a pipe or other cylindrical member, the conventional manner of installing such thermoswitch is by clamping it to the outer cylindrical surface. Since such cylindrical members may be of varying diameter, close contact with a standard thermoswitch is possible over only a small area; and thermoswitches so installed do not respond to changes in temperature of the enclosed liquid with precision and exactness. For example, in a water-filled baseboard heater to limit the temperature which may be developed to say 300° F., it may be necessary to set the limit switch at 290° or less, to be sure the desired 300° limit is not from time to time exceeded.

In baseboard heaters of the type shown in U.S. Pat. No. 3,281,574, a sealed-off well for a thermoswitch has been provided within the reservoir, so that the entire well surface will be subjected to the heat of the liquid. The construction of such wells adds excessively to the construction cost, especially since conventional thermoswitches do not sense temperature over an outer cylindrical face which might be fitted in such a wall.

SUMMARY OF THE INVENTION

The present invention, applied at the end of a preferably cylindrical tubular member containing a fluid whose temperature is to be sensed, is a thermoswitch installation characterized by exceptional response characteristics. An end cap, preferably formed of ductile metal such as copper, is sealed onto such cylindrical member, as by brazing. Closely adjacent to its end surface, the cap has an outstanding flange. Formed in the end surface is a planar, indented temperature-sensing face, which may be circular assuming the thermoswitch to be accommodated therein has a corresponding circular temperature-sensing face.

A clip formed of springy metal includes a base portion and a thermoswitch-holding portion extending at an angle thereto, and preferably substantially parallel to the planar indentation. At the other end of the base portion, leg members extend outward and are thence bent angularly to be substantially opposed to each other and reaching to a spacing less than the diameter of the cap. The legs have slots lying in a common plane; preferably the base portion also has a slot in this plane; the slots being wider than the thickness of cap flange.

On mounting the thermoswitch to the clip, the slotted leg members are engaged over opposed portions of the cap flange, on which the slot in the base portion is also fitted; and the flange portions projecting therethrough may be staked back. The thermoswitch temperature-sensing face will thus be spring-urged to make and maintain intimate contact with the planar surface indentation of the end cap.

BRIEF DESCRIPTION OF THE DRAWINGS

FIG. 1 is a side elevational view of the present installation in place on a water-filled baseboard heater tubing assembly, shown fragmentarily and partly schematically.

FIG. 2 is an enlarged, somewhat fragmentary view of the left end portion of FIG. 1.

FIG. 3 is an end view as seen from the left of FIG. 2.

FIG. 4 is an auxiliary view of the spring clip as seen 5 along line 4-4 of FIG. 3, prior to installation.

DESCRIPTION OF THE PREFERRED EMBODIMENT

In the embodiment illustrated the invention is used as 10 a limit switch installation in a baseboard heater tubing assembly generally designated *a*. Such assembly includes a horizontal cylindrical reservoir tube *b* leading to a reducer section *c* to which a lower horizontal tube *d* is brazed. The tube *d* leads into an upward-extending 15 tube *e* which at midheight has a T-connection to an upper horizontal tube *f*, but projects thereabove curvingly to provide a closed-end expansion tube portion *g*. The upper horizontal tube *f*, equipped with closely spaced fins *h*, extends above and parallel to the lower 20 members *b*, *c*, *d*, to join a riser tube *j* which is brazed into the upper surface of the reservoir tube *b* near its end opposite the reducer section *c*.

Onto the outstanding end of the reservoir tube *b* shown enlarged in FIG. 2, I sealedly attach, as by brazing, 25 an end cap generally designated 10. The cap 10 is formed of a brazable copper, characterized by ductility. It includes an end surface 11 having a cylindrical drawn margin 12, which terminates in an outstanding flange portion 13. The cap margin 12 is sealedly brazed 30 to the reservoir tube *b*.

The end surface 11 of the cap 10, as seen in FIGS. 2 and 3, has two outward drawn tubular nipples 14, one of them being somewhat below its midheight. In them are sealedly mounted the outstanding electrical terminal ends *k* of a conventional hair pin shaped electrical resistance heater *m*, which extends therefrom inward 35 into the reservoir tube *b*, in a canted plane. The terminal ends *k* are to be connected to a power source, not shown, controlled by the thermoswitch hereafter referred to.

A thermoswitch generally designated *n*, of a conventional type is shown installed somewhat above the canted resistance heater *m*. The thermoswitch *n* is a type adapted, through conventional circuitry not 45 shown, to break the electrical circuit to the resistance heater *m* when water in the reservoir tube *b* reaches a predetermined limit temperature. It has a generally cylindrical body *o* and a planar circular temperature-sensing end face *p*, whose diameter is slightly larger 50 than that of the switch body to provide a mounting shoulder *q*.

A precisely planar surface indentation 17, of such size to closely accommodate the thermoswitch surface *p*, is stamped or drawn in the cap end surface 11. The 55 indentation 17 is bounded by a shallow sloping wall 18 which aids in locating the face *p* of the thermoswitch *n* in precise position.

To mount the thermoswitch *n*, a spring metal clip generally designated 20 is provided. It includes a flat 60 base portion 21, best seen in FIG. 3 with a pair of spring-like leg members 22 extending laterally outward therefrom and bent at a spacing corresponding somewhat to the diameter of the end cap 10 to provide opposed leg portions 23. In unstressed condition prior to 65 installation they are somewhat inclined toward each other, as seen in FIG. 4. When installed as shown in FIG. 3 they are spread from such normal position to

grasp the end cap 10 by its flange portion 13. To provide such grasp, aligned slots 24 are provided in the clip opposed leg portions 23, and a base slot 25, aligned therewith, is also provided. The slots 24, 25 are slightly greater in width than thickness of the cap flange 13 so that, as seen in FIGS. 2 and 3, parts of the flange portion 13 will project therethrough. The clip 20 may be staked in place by bending back projecting parts of the flange portion 13, as the bent back flange part 26 of FIG. 2.

From the clip base portion 21 there extends at a fixed spacing from the slots 24, 25 a thermoswitch holding portion 27, which may be tab shaped as shown in FIG. 3 and rounded inwardly as seen in FIG. 4. It is bent to an angle nearly 90° and which, on installation will be substantially parallel to the end cap planar surface 17. It includes a circular cutout 28 through which the cylindrical body of the thermoswitch *n* is fitted. The portion 27 presses against the shoulder *q* of the thermoswitch, retaining it securely as shown in FIG. 2.

Inasmuch as the clip 20 is formed of springy metal, the temperature-sensing face *p* will be continuously urged by it into close contact with the planar surface indentation 17 of the end cap 10. Retention is assured by staking back the parts of the cap flange portion 13 which project through the clip slots 24, 25, as the part 26 seen in FIG. 1.

Installations made according to the present invention have shown excellent and reliable response to changes in temperature of water within the reservoir tube *b*. Where, for purpose of safety, the tubing assembly *a* is to be limited to a pressure which corresponds to a temperature of 300° F., a thermoswitch *n* may be selected to break the circuit at almost precisely this temperature, and it will function reliably regardless of such known variables as changes in ambient temperature. In contrast, installations made as taught by the prior art are so affected by such variables as to cut off the heating current over an undesirable wide range of temperatures; to provide for such range it was necessary to select a thermoswitch setting at least 10° lower than the desired 300° F. limit. This reduced the maximum utilizable heating capacity of the heater, a disadvantage which the present invention has overcome.

From the present specification, modifications in detail will be apparent to those skilled in the art.

I claim:

1. For sensing the temperature of a fluid within and adjacent to an end of a cylindrical member, a thermoswitch installation including an end cap sealed to such cylindrical member, and a thermoswitch external to and having a temperature-sensing face in contact therewith, characterized in that the thermoswitch temperature-sensing face is planar, and the end cap has a planar surface indentation of such size as to accommodate said temperature-sensing face of the thermoswitch.

60

the end cap further having an outstanding flange, in combination with clip means to mount the thermoswitch to opposed portions of the end cap flange and urge its temperature-sensing face into contact with said planar surface indentation, wherein the clip means is formed of springy metal and includes

a base portion, slotted spring-like leg members extending outward therefrom and opposed to each other, the leg members having slots greater in width than the thickness of the cap flange and lying in a common plane, and a thermoswitch-holding portion extending angularly from the base portion and when mounted being substantially parallel to said planar surface indentation of the end cap,

whereby on mounting the thermoswitch in the said holding portion so extending angularly from the base portion, and on mounting the clip means with its slotted leg members embracing opposed portions of the flange of said end cap, the temperature-sensing face will be urged into intimate contact with said planar surface indentation of the end cap.

2. A thermoswitch installation as defined in claim 1, wherein

the end cap is formed of a metal characterized by ductility whereby flange portions extending through said slotted leg members may be staked thereover.

3. A thermoswitch installation as defined in claim 1, wherein

the base portion of the clip means has a lateral slot aligned with the slots in said leg members, whereby to embrace a third portion of the flange of such end cap.

4. For mounting a thermoswitch of the type having a temperature-sensing face in contact with the flanged end cap of a fluid containing member, a clip formed of springy metal and including a base portion,

spring-like leg members extending outward therefrom and opposed to each other, a lateral "detent means formed" in the base portion and aligned detent means formed in each of the leg-like spring members, the said detent means being greater in width than the thickness of such cap flange whereby to be capable of engaging edge portions of the flange, and

a thermoswitch-holding portion extending outwardly angularly from the base portion, "in the same direction as the leg members" "said holding portion being spaced relative to the said detent means in the base portion and leg members a distance such that when said detent means engage the cap flange edge portions." a thermoswitch positioned in said holding portion will be urged by it into contact with the end cap.
